East Bridgewater, Mass., a corporation of Mas-
sachusetts

Application December 29, 1941, Serial No. 424,742

4 Claims. (Cl. 142—56)

Our present invention relates to improvements in last turning or like lathes and has for its objects improvement of the speed and accuracy of turning operations and increased efficiency and economy in the operation and maintenance of such lathes.

In the development of these lathes, there long has been indicated the advantage of small diameter cutters, but their use has heretofore involved such various difficulties and conflicts of possible remedial factors that their adoption has been retarded.

Noticeable difficulties with lathes prior to our invention were inaccurate and rough cutting, vibration, the development of excessive heat, the necessity for frequent sharpening and replacement of the cutting elements, and for other service. These difficulties all contribute to limit the productive capacity of the lathes and the quality of the products turned therein.

These general objections may be more readily appreciated by an analysis of certain elements of lathes now commonly used and of these elements, the cutting means merit special consideration.

The cutting means of commercially used last turning lathes consisted of finishing cutters and roughing cutters, the latter being in effect rotary chisels employed to shape the block to be turned to permit finishing by the removal of relatively thin chips by the finishing cutters.

We provide cutting means in which a series of cup shaped cutters are utilized and since ground cutting edges retain their sharpness longer when employed to remove substantial amounts of stock, we so space the cutters relative to each other and to the axis of rotation of their supporting shaft that cutters are available to rough the block to a shape insuring that the principal roughing cutter and the finishing cutter each have a constant and substantial amount of stock to remove.

In order to provide a simple and rugged support for the cutters and to insure the dissipation of heat developed by high speed lathe operations, we provide a unitary cutter head and drive shaft supported in bearings with its drive pulley on its end. This construction not only insures cool operation, but also makes belt replacement extremely easy. The remarkable efficiency of this construction is evidenced by greatly increased service of the driving belts which hitherto have, because of the heat factor, required frequent replacement.

To insure maximum accuracy and efficiency of lathes in accordance with our invention, we have provided the carriage supporting the cutting means with a motor mount centering its weight and the weight of the unitary cutter shaft and head so that vibration is eliminated as the carriage traverses its supporting bed.

Such and other advantages will more fully appear in the discussion of the improvements herein involved and illustrated in a lathe of generally standard type to such extent as seems necessary as a basis for the description of and claims for the present invention, but not at all as to their limitation, as other machines are in use that may be substantially improved by additions to or substitutions for inefficient parts of their present combinations.

In the drawings:

Fig. 1 is a front elevation of a lathe according to our invention.

Fig. 2 shows the lathe of Fig. 1 in end view.

Fig. 3 is a plan view of the same with certain parts omitted for clarity in illustration.

Fig. 4 is a fragmentary side view showing the unitary cutter head and drive spindle.

Fig. 5 is a partly sectioned end view of the same.

Fig. 6 is a schematic development showing the relation of the cutting elements to each other.

Fig. 7 shows, in direct side elevation, the cutting means, the drive therefor and the supporting carriage.

Fig. 8 is a development of the relations of the cutting elements similar to Fig. 6 but with the cutting elements longitudinally spaced to clarify their operative relation, and

Fig. 9 shows the relation of the axis of the cutting head to the cutters and to the axis of the block to be turned.

The lathe illustrated comprises, in general, means to support and rotate a model and the block to be turned, a unit comprising a model wheel and the cutting head and its drive, and a drive to feed the unit so that the model wheel and the cutting head traverse the rotating model and the rotating block, the supporting means for which are free to swing so that the action of the cutting means follows the contours of the model.

The lathe consists of a bed 1 and an overhead frame 2 supported on legs 3. The overhead frame 2 pivotally supports the swing frame 4 as at 5. Conventional rotatable model supports are indicated at 6 and 7 and similar rotatable supports

8 and 9 are provided to support the work to be turned. The supports 6 and 8 include gears 10 and 11, respectively, meshing with gears 12 and 13 on the drive shaft 14 journaled in the swing frame 4.

The drive shaft 14 carries a gear 15 meshing with a worm gear 16 the shaft 17 for which carries a pulley 18 connected to the pulley 19 of the motor 20 by the belt 21 so that the model, held by the supports 6 and 7, and the block to be turned, held by the supports 8 and 9, are positively rotated.

The model wheel 22 to contact the model and control the position of the swing frame 4 is conventionally adjustably mounted on a carriage 23 slidably supported on parallel ways 24 on the bed 1. A carriage 25 slidably supported on the lathe ways 24 carries the cutting means and its motor, later to be described.

The carriage 25 is driven by the motor 26 which has a belted connection 27 with the shaft 28 having a worm gear 29 in mesh with the gear wheel 30 the shaft 31 of which is journaled in the bed 1 and carries a gear 32 in mesh with the rack portion 33 of the carriage 25.

The carriages 23 and 25 are interconnected by the adjustable linkage 34 one end of which is pivotally attached to the carriage 25 and the other end of which is adjustably pivoted to the lever 35 adjustably fulcrumed as at 36. This is conventional "grading" mechanism whereby equal, greater, or less movement of the carriage 23 results upon movement of the carriage 25. As grading operations are conventional we have not described them in detail or the mechanism by which they are effected.

From the foregoing it will be apparent that the model wheel 22 and the cutting mechanism move as a unit on the bed 1 with the model wheel 22 in contact with the rotating model. The swing frame 4 is actuated by such contact to move the work to be turned nearer to or farther away from the cutting mechanism to shape the block according to the model.

In order to control the swinging of the frame 4, it has been the practice to provide a weight to insure the constant contact of the model with the model wheel 22. In prior lathes, such weights were so mounted that their influence was not constant. We connect the frame 4 to a crank 37 by a link 38 and mount on the crank shaft 37a a pair of collars 39 to which the weight 40 is eccentrically pivoted so that its influence on the frame 4 is constant as the frame 4 swings towards or away from the vertical.

The lathe as thus far described is conventional except for motor drive for the carriages, the motor drive for the model and the block to be turned, and for the counterweighting of the swing frame 4. We have omitted from the drawings many details of construction to simplify the drawings as these are not essential to a proper understanding of the construction and operation of lathes in accordance with our invention.

We provide the carriage 25 with a mount 41 consisting of a pair of spaced standards 42 set diagonally of the lathe ways 24. The standards 42 include anti-friction bearings, as for example roller bearings 43 in support of the shaft 44.

The rearwardly disposed portion of the shaft 44 extends beyond the carriage 25 and supports a pulley 45 and a flywheel 46 and its forwardly disposed portion is reduced as at 47 to insure the accommodation of work to be turned without contact therewith.

At its outer end the portion 47 is milled to form pairs of webs 48, 49 and 50 and 51. The faces 48a and 49a of the webs 48 and 49 are in radial alignment with respect to the axis of the shaft 44 and at right angles to the radially aligned faces 50a and 51a of the webs 50 and 51. Each of the webs is formed with a radially enlarged portion 52 drilled to permit the detachable mounting of cup-shaped cutters. As the cutters are identical, I have indicated them generally as at C in certain views. The cutters C are supported and held against rotation by bolts 53 carrying nuts 54 by which the cutters C may be tightly seated against the radially disposed web faces or loosened to permit them to be partially rotated when the operative portions of their cutting edge become worn, thereby bringing into an operative position a sharp portion thereof. To hold the bolts 53 against rotation, we form them and the holes through which they extend slightly oval. The rear face of each web is milled out as at 55 to accommodate a portion of the cutter C carried by the adjacent web.

As shown in Fig. 9, the axis A of the shaft 44 is disposed at an angle, preferably of 30°, to the axis of the work to be turned defined by the supports 8 and 9 and indicated at B in Fig. 9.

While each of the cutters C is identical, their function is individual and hence we have in Figs. 4, 5, 6, and 8 identified the four cutters employed at 56, 57, 58 and 59.

The cutter 56 is the finishing cutter and as may be most clearly seen in Figs. 6 and 8, it is disposed a maximum distance from the axis A. The cutter 57 is placed inwardly longitudinally and radially of the cutter 56 to provide a definite but substantial amount of work for the cutter 56. While the cutter 57 is the roughing cutter, we employ the cutters 58 and 59 to insure that the amount of work required of the cutter 57 is constant. The cutters 58 and 59 are spaced radially inwardly of the cutter 57 an equal distance but are spaced axially therefrom and from each other to insure cooperative rough shaping of the wood so that the work of the cutter 57 is constant. As shown in Fig. 9, the line of the cutting edges may be considered as defining an angle of 43° to the axis B.

We refer to the portion 47 of the shaft 44 and the cutters mounted thereon as the cutting head and in accordance with our invention, the head is perfectly balanced. For example, if one of the cutters is reground we restore the desired balance by adding a shim between the cutter and the face of its supporting web. Such shims are of course thin and accordingly we have only indicated at S in Fig. 5 the location thereof when necessary to insure the balance of the cutting head.

The shaft 44 is rotated by the motor 60 through the belt 61 interconnecting the motor pulley 62 and the pulley 45. In accordance with our invention, we insure smooth and accurate last turning by so mounting the motor 60 that the carriage 25 rests evenly on the lathe ways 24 at all times.

We accomplish this result by providing the carriage 25 with a hanger 63 depending from the carriage 25 in its central zone. The base of the motor 60 is bolted to a plate 64 the rear part of which is pivotally connected as at 65 to the hanger 63. We form the front part of the plate 64 with a pair of ears 66 for a pin 67 passing through a bearing 8 having a threaded stem 69 extending through the bracket 70 on the hanger 63 and adjustably locked in position by nuts 71. By this

construction, the weight of the motor 60 is centered and the position of the motor 60 may be easily adjusted to place the belt 61 under proper tension. It will also be appreciated that because the pulley 45 is on the end of the shaft 44 so that the belt 61 is externally of the carriage 25, it may be quickly and easily replaced.

Our invention has the further advantage of insuring cool operation. As the shaft 44 is of substantial diameter and the support for the cutters is integral therewith, heat is rapidly conducted away from the cutting head. The effectiveness of our combination in dissipating heat is particularly noticeable by the coolness of the belt 61 and its attendant long life.

As we have explained, the disposition of the cutters on the forwardly disposed part of the shaft 44 not only provides a rugged cutter head and eliminates the expensive roughing cutters formerly employed, but also provides for greater accuracy and effectiveness in operation and increased cutter service at a minimum expense. With lathes embodying our invention, the time required to turn lasts may be reduced from eight or nine minutes to three or four minutes, and if desired, a last can be turned from an unslabbed block thus saving the expensive and dangerous rough shaping of the block in accordance with usual practice. The production capacity of lathes in accordance with our invention is further increased by the fact that the cutters remain sharp for long periods and are interchangeable one with the other.

While the effectiveness of our cutting means is of great importance, our novel motor support is essential in that it insures steadiness in the carriage and the fact that our combination insures cool operation contributes materially to the effi-

ciency and economy of lathes in accordance with our invention.

What we therefore claim and desire to secure by Letters Patent is:

- 5 1. Cutting mechanism for turning irregular objects, said mechanism comprising a rotatable cutter supporting member having an end formed with a plurality of webs, at least one set of corresponding faces of which are equi-angularly spaced, each of said webs including a radially enlarged portion and the other set of corresponding web surfaces being recessed to an extent sufficient to define with an adjacent enlarged portion a seat, one of said seats being disposed adjacent the end of said member a predetermined distance from its axis, and the other seats being successively disposed radially and axially inwardly of said first seat and from each other, and a cup-shaped cutter anchored against each of said seats.
- 10 2. The mechanism of claim 1 in which the first-named set of web surfaces are radially disposed.
- 15 3. The mechanism of claim 1 in which there are four webs and the first-named set of web surfaces are radially disposed and the other set of web surfaces are disposed at right angles thereto.
- 20 4. Cutting mechanism for turning irregular objects, comprising a rotatable cutter-supporting member having an end formed with a plurality of webs extending radially of the cutter axis, at least two of said webs having adjacent surfaces disposed at an angle to each other, one of said surfaces being substantially flat and the other surface being recessed to an extent sufficient to define with said flat surface a seat, and a cup-shaped cutter anchored in said seat.
